UNITED STATES PATENT OFFICE.

SAMUEL ABRAMS AND JOSEPH NEFF, OF CHICAGO, ILLINOIS.

MASTER TEMPLATE FOR LAYING OUT PATTERNS.

Application filed April 2, 1924. Serial No. 703,616.

This invention relates to improvements in master templates for laying out patterns from previously determined measurements and consists of the matters hereinafter described and more particularly pointed out in the appended claim:

The primary object of the invention is to provide a novel and improved means by which perfect patterns of different sizes as measured by a tailor may be quickly and accurately laid out.

This object of the invention as well as the many advantages thereof will more fully appear as we proceed with our specification.

15 In the drawings:—

Fig. 1 is a plan view of template parts, embodying our invention, for laying out patterns for coat backs.

20 Fig. 2 is a similar view of template parts for laying out patterns for coat fronts.

Fig. 3 is a view of the template parts for laying out patterns for the sleeves of a coat.

Fig. 4 shows a pattern sheet and the manner of laying out a pattern thereon for coat 25 backs.

Fig. 5 shows a pattern sheet and the manner of laying out a pattern thereon for coat fronts.

30 Figs. 6 and 7 illustrate the manner of using the template shown in Fig. 3 when laying out the top and under sleeve parts of a coat.

The invention is herein illustrated and will be described in connection with templates used in laying out the patterns for an ordinary box coat of a man's suit of clothes, but the invention is not intended to be limited thereto, as the same principles of invention are embodied in templates used for laying out patterns for vests and trousers, which 35 it is thought unnecessary to illustrate and describe in detail here.

Referring, now, in detail to that embodiment of the invention illustrated in the accompanying drawings and more particularly to Fig. 1, 10 indicates the template for the top part of a coat back and 11 indicates the template for the bottom part of a coat back, both of which are made of a fairly stiff and strong paper, as are other template 40 parts to be described later.

50 The template part 10 is of such form as to include the standard outline of a back seam 12, a collar seam 13, shoulder seam 14 and arm pit 15, there being an arbitrary bottom edge or margin 16 which is made on the plane of a chest or breast measurement line as used

by tailors in measuring a person for a suit of clothes. Said edge as illustrated herein is substantially straight and horizontal except at that end where said edge meets the arm pit line 15 where it is inclined as at 17. In the margins 12 and 17 of said templates are a plurality of indicia notches 12^a and 17^a respectively, which are numbered from "34" to "44" inclusive. These numerals indicate in inches, the usual sizes of standard measurements as used in the tailoring trade. In the margin or edge 15 is provided a single notch 15^a which acts as a guide when inscribing a predetermined mark upon a pattern sheet. At the junction of the margins 13 and 14, and 14 and 15 respectively, are provided rows of perforations 13^a and 14^a respectively which like the notches 12^a and 17^a are numbered from "34" to "44" inclusive. 55

In the lower left and right hand corners of the template part 10 are printed or otherwise inscribed the letters "A" and "B" respectively. 70 The template part 11 has side margins 18 and 19 of standard outline corresponding to the side and rear seams for a coat back. In the margin 18 is a notch 18^a. The top margin 20 is made on the breast line measurement before mentioned while the bottom margin 21 is curved on the line of the bottom edge of the skirt of the coat. In the upper left and right hand corners of the template part 11 are similar indicia letters "A" and "B" as before mentioned. 75

80 In Fig. 2 is illustrated the template parts 22—23 and 24 for coat front patterns. The template part 22 has an arm hole margin 25, shoulder seam margin 26, neck or collar margin 27 and lapel fold line 28 all made on standard outlines, while the bottom margin 29 is made straight on the chest line. At the junction or corner of the margins 25 and 26 are provided notches 25^a numbered from "34" to "44" respectively, and in the margin 25 is a single notch 25^b. Notches 28^a similar to the notches 25^a are provided in the margin 28 near the margin 27. A row of holes 27^a numbered from "34" to "44" is provided at the junction of the margins 26 and 27, while a single notch 29^a is formed in the breast line 29 and above the same is placed the letter "A". Between the notches 25^b and 29^a and spaced from the margin 29 is a perforation 29^b which positions the breast 95 pocket of the coat front. 100

105 The template part 23 for the bottom part

of the coat front includes a lapel extension 30 which has drawn upon it, a line 31 indicating the fold line of the lapel which corresponds to the margin 28 of the template part 5 22. The margin 32 which is taken on the breast line has two sets of notches 32^a and 32^b both numbered "34" to "44" inclusive. In the edge 33 of the template which is the button and button hole margin of the template, 10 is a notch 33^a arranged on the breast line and in line therewith in the opposite margin 34 is a similar notch 34^a. In the bottom margin 35 of the template part 23 which corresponds to the hip line in tailors' measurements, are notches 35^a numbered "34" to "44" respectively. Just above the said bottom margin are holes 35^b—35^b which position the pocket openings and in the margin 33 are spaced holes 33^b for positioning the buttons 15 and button holes.

The template 24 has two longer side margins 36 and 37 and in the first margin is formed a notch 36^a while in the other margin are notches 37^a and 37^b, the notch 37^a being arranged in a position corresponding to the breast line. The margin 36 corresponds to the gore lines for the "taking in" at the waist line while the margin 37 corresponds to the bottom part of the back seam.

30 In Fig. 3 the template parts for laying out the top and under sleeve parts are illustrated. 38 indicates the template part for laying off the top end of both sleeve part patterns and 39 indicates the template part for laying off the seam outline of said sleeve part. The template 38 has a bottom margin 40 which is made on the breast line, and two side margins 41 and 42 respectively. The margin 41 has an outline conforming to the 45 top or shoulder end of the top sleeve portion while the margin 42 has an outline conforming to the arm pit end of the under sleeve portion of the pattern to be laid out. In the margin 41 are formed a plurality of notches 41^a numbered "34" to "44" while near the breast line margin is a single notch 41^b, a perforation 41^c being provided in the template a short distance from the notches 41^a. In the margin 42 where it meets the margin 50 41 is a plurality of notches 42^a (numbered "34" to "44") while below the same is a single notch 42^b.

The template 39 has side margins 43 and 44, for the front and rear seams of the sleeve and in each of said margins is a notch 43^a and 44^a respectively arranged on the breast line before mentioned.

Assume that the pattern to be made is a size "36". A pattern sheet 45 (see Fig. 4) 60 is laid upon the work table and a base or meridian line 46 is drawn thereupon. The template 10 is placed with its base edge 16 on the base line 46 on the pattern sheet. With aid of a pencil, points 47 are inscribed on the pattern sheet by marking through the

notches and perforations "36" of the notches and perforations 12^a—13^a—14^a and 17^a respectively. The template is then shifted about so that the edges 12—13—14—15 and 17 may be used as guides to draw the lines 48 70 as shown in Fig. 4. The template 11 is next used. The edge 20 is brought into position on the base line 46 of the pattern sheet with the upper left hand corner (bearing the letter "A") in register with the left hand point 47 on the base line 46 of the pattern sheet. With the edge 18 as a guide the line 49 is drawn. The template is shifted to the right until its upper right hand corner (bearing the letter "B") registers with the point 47 at the right hand end of the base line and a line 50 is drawn on the pattern sheet with the edge 19 as a guide. Thus a pattern for the back of a coat, size "36" is drawn upon the pattern sheet. The pattern sheet is next cut about the pattern line thus drawn, allowance being made for the seams.

In laying out a coat front, a pattern sheet 51 is laid upon a table and a base line 52 is drawn upon the same. The template 22 is 90 placed upon the sheet with its base line or edge 29 on the base line on the pattern sheet and a point 52^a made on said line 52 by marking with a pencil in the notch 29^a, and a similar mark is made through the number "36" notches and holes of the notches 25^a and 28^a and 27^a after which the template is shifted so as to be used as guides for drawing lines between said points corresponding to the edges 25—26—27 and 28 of the template.

The template 23 is next used by placing its top edge 32 along the base line 52, the "36" notch of the notches 32^a being brought into register with the point 52^a previously made on the base line through the notch 29^a. This positions the template. Marks are pointed off on the pattern sheet through the "36" notches of the group of notches 32^b and 35^a and marks are pointed off on the pattern sheet through the holes 33^b (for the buttons and button holes) and through the holes 35^b—35^b (for the pockets). The pattern lines are then drawn about the edges of the template.

After the template is removed from the pattern sheet, the template 24 is positioned on the pattern sheet with the notch 36^a in register with the mark made through the "36" notch of the group of notches 35^a and with the notch 37^a in register with the mark made through the notch 34^a. This positions said template and lines are drawn about the edges thereof. The template 24 is now turned over with the notches 36^a still in the same position and another line is drawn along said edge to provide the gore lines under the arms as shown in Fig. 5. The skirt part 55^x of the pattern may be made of any desired length.

A line 55 is drawn down on a pattern sheet 56 and the base line 40 of the template 38 is placed thereon. Marks are made on the pattern sheet through the "36" notches 5 of the groups of notches 41^a and 42^a when a line is drawn along the edge 41 from the base 40 to the "36" notch of the group 41^a after which the template is shifted so that the top part of the template may be used 10 in drawing a line 55^a connecting the two marks on the pattern sheet made as before described. The template 39 is then placed in position with the notches 43^a—44^a on the line 55 with the notch 43^a coinciding with 15 that point formed where the line drawn about the edge 41 of the template intersects the line 55 after which a line 57 is drawn upon the pattern sheet with the edge 43 of the template 39 as a guide. The template 20 is shifted to the right until its upper right hand corner registers with the mark made on the pattern sheet through the "36" notch of the notches 42^a, with the notches 43^a—44^a still on the base line when a line 58 is drawn 25 about the edge 44 of the template. This produces the pattern for the top sleeve part.

To make the pattern for the under sleeve part, a base line 59 is drawn on a pattern sheet 60 (see Fig. 7). The base line of the 30 template 38 is placed on the line 59 and a mark is inscribed on the pattern sheet through the "36" notch of the group of notches 42^a and a line 61 is drawn about the edge 42 stopping at the base line 59. The 35 upper left hand corner of the template 39 is placed at the meeting of the base line and the line drawn about the edge 42 with the notches 43^a—44^a on the base line 59 after which the edge 43 is used as a guide for 40 drawing a line 62 which represents the inseam of the under sleeve part. The template 39 is shifted along the line 59 toward the right with the notches 43^a—44^a still on the

base line until the upper right hand corner meets the mark made through the "36" notch 45 of the notches 42^a after which a line 63 is drawn using the edge 44 as a guide. This completes the laying out of the pattern upon the pattern sheet which may be cut out to form, allowance being made for the seams 50 as is usual.

It is apparent that with the aid of our improved template parts, any person may lay out a pattern of any of the standard sizes.

We claim as our invention:—

A master pattern comprising a plurality of template parts consisting of top and bottom parts for a coat back, shoulder, body and back seam parts for a coat front and top end and seam outline parts for a coat sleeve, said top and bottom back parts and shoulder and body front parts being laid out from a common base line adapting them for registration with a line to be drawn on a pattern sheet representing the chest measure, each of the template parts having one or more outline edges of the standard outline of a complete pattern to be made, some of said template parts having corresponding scale marks in the margins thereof graded 70 according to different sizes of waist measure, said scale marks providing for the convenient marking off of points on the pattern sheet in positions correlated to the base line and corresponding to the outline of said 75 template parts, and the said edges of the template parts when positioned on the marked off points on the pattern sheet providing a guide for the drawing of pattern lines upon said pattern sheet.

In testimony that we claim the foregoing as our invention, we affix our signatures this 28th day of March, A. D. 1924.

SAMUEL ABRAMS.
JOSEPH NEFF.
